(57) **CLAIM**

The ornamental design for an eyemask, as shown and described.

DESCRIPTION

FIG. 1 is a front perspective view of an eyemask showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another rear perspective view thereof, showing two eyecups being omitted.

The broken lines shown in the drawings depict portions of the article that form no part of the claimed design.
